CUTTING APPARATUS

Gustave Adolphe Ungar, Pelham Manor, N. Y.,
assignor to S & S Corrugated Paper Machinery
Co., Inc., Brooklyn, N. Y., a corporation of New
York

Application June 18, 1937, Serial No. 148,892

9 Claims. (Cl. 164—68)

My invention relates to novel means of and apparatus for cutting corrugated board or sheet material and more particularly to continuously operating knives arranged to be driven in synchronous speed with the sheet material during the cutting operation.

In cutting corrugated board, for instance, as it is being fed from the corrugator it is necessary, where continuously driven knives are to be employed, that provision be made for varying the speed of the knives during the cutting period as the cycle of the knives are changed for different sizes of sheets to be cut. Thus, for example, if the knife drums are rotating at a speed which will produce synchronism between the knife and the paper for one size length of sheets to be cut, it will be obvious that for another size the necessary changes in the period of the cycle of the knife drum will, unless there is a change within the cycle itself, result in a non-synchronous condition between the knife and the moving sheet.

In order to overcome this, it has been proposed that involved elliptical gears be employed which can be shifted angularly so that the speed during a single cycle is varied, always resulting in a synchronous speed or at least an approximate synchronous speed during the cutting period.

More recently such elliptical gears arrangement has been considerably improved upon by a hydraulic transmission and other forms of drives.

In general, however, these systems are expensive and lack the positive operation which is desirable in these machines. I have discovered that, by the proper interlinkage between the drive and the driven member, which links are adjustable, I may change the speed during a cycle for producing synchronism during the cutting interval without sacrificing any positive action in the drive connection.

Attempts to accomplish this heretofore have not only been complicated and costly but failed to provide corresponding adjustment for insuring synchronous speed between the knives and sheet material during cutting for all sizes of material.

Accordingly an object of my invention is to provide a novel apparatus for and method of cutting corrugated board.

A further object of my invention is to provide an interlocking pin and slot drive connection for obtaining variable speeds during a single cycle to insure synchronism during the cutting interval.

Still a further object of my invention is to

provide a wide range of adjustments which will enable any desired length of material to be cut while insuring synchronism during the cutting interval.

Still another object of my invention is to provide a novel speed adjustment between a driving and driven shaft.

Another object of my invention is to provide means for adjusting the axial relation between two shafts for obtaining speed variations therebetween in a cycle.

There are other objects to my invention which, together with the foregoing, will appear in the detailed description which is to follow in connection with the drawings in which:

Fig. 1 is a perspective view of one form of my invention employing a link connection.

Fig. 2 is a cross-section through 2—2 of Fig. 1.

Fig. 3 is a detail of Fig. 2.

Fig. 4 is a perspective view of another form of my invention employing a pin operating in a slot.

Fig. 5 is a perspective view of another form of my invention.

Figs. 6 to 13 are illustrations showing the link and slot operations for different adjustments of Figs. 1 and 4.

Fig. 14 is a set of curves showing the relation between the movement of the control member of the variable speed transmission and the axial movements of the drive shafts.

Figs. 15 to 19 are schematic illustrations of other methods for obtaining synchronism between the knife and paper in a continuous knife-cutting machine.

Figs. 20 and 21 are schematic illustrations showing the movements of the knives for the construction shown in Figs. 18 and 19.

Referring now more specifically to Fig. 4, I have disclosed the usual Reeves drive comprising the cones 12 and 13 joined by the continuous belt 14. The cone 13 is mounted on the main drive shaft 15 from which power for operating the mechanism to be described is obtained. Secured to and rotatable with the shaft 15 is a sprocket 16 which engages the sprocket chain 17 which in turn rotates sprocket wheel 18 mounted on the shaft 19 which carries thereon the feed roll 20 cooperating with the upper feed roll 21. Between the feed rolls 20 and 21 the web 22 is advanced forward in the direction indicated to be cut in predetermined lengths by the knives 23 and 24 mounted on drums 25 and 26 respectively.

The cone 12 is mounted on and drives the

35

40

45

50

55

shaft 31 which carries on its end a sprocket wheel 32 carrying the sprocket chain 33 the opposite end of which meshes with the sprocket wheel 34. Sprocket wheel 34 in turn is keyed to shaft 35 which carries at one end thereof gear 36 which through the idler gear 37 with which it meshes drives the gear 38. The gear 38 is keyed to the shaft 39 one end of which carries a crank 41. To one end of the crank 41 and extending substantially at right angles from the plane thereof a pin 42 is secured and is arranged to drive the bifurcated crank 43 in which it is slidably positioned. The bifurcated crank 43 in turn is keyed to the shaft 44 which carries at 10 the other end thereof the knife drum 26 bearing the knife 24. A gear 44' also keyed to shaft 44 meshes with and drives a gear 45 which is keyed to the shaft 46 which carries rotatably therewith the drum 25 of the knife 23.

From the above, the normal operation of the machine, without taking note of the adjustments hereinafter described, will be clear. As the Reeves drive transmits power over the shaft 31 the gear 38 is rotated, in turn driving the shaft 39 and the crank attached thereto 41 together with the pin 42 about the axis of shaft 39 as a center. As the pin 42 rotates about the shaft 39 as its center it will drive the bifurcated crank 43. In the specific adjustment shown in Fig. 4, where the shaft 39 lies below shaft 44, the pin 42 is sliding toward and away from shaft 44 in a plane at right angles to its axis during each revolution by reason of its fixed relation with respect to shaft 39.

Assuming for the purpose of the present illustration that the shaft 39, which, as will be explained hereinafter, is adjustable with respect to the fixed knife shaft 44, is below the shaft 44 as in the present case; it will be obvious that angular velocity θ of the shaft 39, when the crank 41 and the pin 42 reach the position shown in Fig. 4 with the pin 42 just above the shaft 44 and at its closest approach to shaft 44, will produce an angular velocity $r\theta$ of shaft 44 which is greater than the angular velocity θ of shaft 39 due to the fact that the driven shaft 44 has a smaller acting radius than the driving shaft 39 in the position shown, the relationship between the angular velocities of the shafts 39 and 44 being in fact a ratio r of the acting radii.

θ =angular velocity of shaft 39.

r =acting radius of shaft 39 ÷ acting radius of shaft 44.

$r\theta$ =angular velocity of shaft 44.

It will be obvious that in every position of crank 41 and pin 42 within the bifurcated member 43, the relationship between the angular velocities of shafts 39 and 44 will be a function of the ratio r between the acting radii of shafts 39 and 44.

Thus, when the pin 42, in the course of its revolution, has turned 45° from the position illustrated in Fig. 4, it will be obvious that the said pin 42 will have slid outwardly in the slot of the bifurcated member 43 and away from the shaft 44, and the acting radius of shaft 44 will increase approaching the acting radius of shaft 39 so that the ratio r between the acting radii will become smaller and the angular velocity $r\theta$ of shaft 44 will be reduced.

Finally, when the pin 42 has turned to a position beneath the shaft 44, the pin 42 will have slid in the slot of bifurcated member 43 toward its outermost position and away from the shaft

44, and the acting radius of shaft 44 will have increased so that it will be greater than the acting radius of shaft 39 so that the ratio r between the acting radii of shafts 39 and 44 will be less than a unit, and the angular velocity $r\theta$ of shaft 44 will be less than the angular velocity of shaft 39.

In this manner the angular velocity of the rotation of the shaft 44 throughout a single revolution is changed and the particular position of the shaft 44 at which it is rotating in synchronism with the paper may be predetermined in order to set the knives for cutting during this period.

When now it is desired to change the length of the cuts (and to this end the Reeves drive is changed for either decreasing or increasing the R. P. M. of the knife drums 25 and 26), the relative position of the pin 42 within the slot of the bifurcated member 43 at the cutting period is correspondingly changed by shifting or adjusting the position of the shaft 39 (about which pin 42 rotates) with respect to the shaft 44. That adjustment will now be described with reference to the Reeves drive.

It will be noted that the bifurcated member 51 is mounted for axial movement on the screw 52 which is manually driven through the handle 53. The screw 52 is part of shaft 52' which carries at its opposite end a screw 54 on which a nut 55 is arranged for axial movement. Extending from the nut 55 is pin 56 extending in the slot formed by the bifurcated member 57 which is carried on the shaft 58 suitably supported in a bearing 59. The shaft 58 carries a crank 61 rotatable therewith: to the opposite end of crank 61 there is secured a link 62, the other end of which is secured through a pin 63 on the slideable frame 64 which is adapted to slide in the channel 64'. Frame 64 has a curved slot 65 in which there is slidably mounted a roller follower 66 connected through a pin 67 to the lever 68 which rotatably carries the shaft 69 on which is secured the idler 37 and which lever may also turn about the shaft 69 as a fulcrum. At the other end of the lever 68 the shaft 39 is rotatably mounted.

When the handle 53 is rotated the bifurcated member 51 moves the belt 14 to either increase or decrease the R. P. M. of the knife drums in a manner now known in the art. Simultaneously the screw at the opposite end 54 will move the nut 55 axially and through the bifurcated member 57 cause the link 62 to move block 64. Depending upon the direction in which block 64 is moved, the roller follower 66 will be raised or dropped by reason of the curvature of the slot 65 and will move the lever 68 about 69 as a pivot causing a movement of the shaft 39 toward or away from the shaft 44 in a plane at right angles to the axes of such shafts, the said axes, however, remaining parallel to each other.

It is now assumed that the knife drums are approximately 9.5 inches in diameter when measured on a line running from the knife edge 63 through the axis, or that they are thus exactly 30 inches in circumference; and that the paper moves past the knives at the rate of 100 feet or 1200 inches per minute. It is further assumed that the size of sheets desired to be cut is 120 inches. It is obvious that the knife drums should revolve at the rate of 10 R. P. M. so that the knives will perform ten cutting operations per minute. It is further assumed that the permanent ratio selected between shafts 31 and 39 is 7-

five to one; therefore, to produce 10 R. P. M. on the knife drums, an output speed of 50 R. P. M. is required on shaft 31 of the Reeves drive.

It is obvious, however, that with 10 R. P. M. of the knife drums whose circumference is 30 inches, the average angular velocity at the circumference of the drums where the knives are located is only 300 inches per minute or exactly one fourth of the speed of the paper. Unless the speed of the knife drums can be increased to the speed of the paper at the time of cutting it will be apparent that the knives will tend to rip or tear the paper and that they will not make a clean cut.

15 The means for varying the speed of rotation of shaft 44 previously described are now applicable here. In Figs. 6, 8, 10 and 12, I have disclosed these movements of the shaft 39 which are effected by the adjustments made through the screw 54. When, as shown in Fig. 6, the shaft 39 is adjusted for its maximum position away from shaft 44, the ratio between the acting radii of shafts 39 and 44 at the moment when pin 42 is intended to be directly above shaft 44 will 20 be four to one.

25

$$r = \frac{4}{1}$$

$$\theta = 300$$

30 At that moment the angular velocity of the shaft 44 will be: $r\theta$ as previously described; and making the proper substitutions for the symbols, the angular velocity of shaft 44 at the knife edge circumference of the knife drum will be 4×300 , or 1200 inches per minute. It will be obvious that θ can also represent merely the rate of revolutions per minute at a given moment so that taking θ as 10 we would get a rate of 40 R. P. M. of shaft 44 at the moment when pin 42 is directly above shaft 44 and thus arrive at the angular velocity of 1200 inches or 100 feet per minute in the same manner.

As the position of pin 42 relative to the axis 45 of shaft 44 changes during a single revolution, the speed of the knife drum decreases as the acting radius 44-42 increases due to the sliding movement of the pin 42 in the slot formed by the bifurcated member 43. Therefore, for each 50 revolution, the average speeds of shafts 39 and 44 are equal.

In the illustration given, with the assumption of the paper moving at the rate of 100 feet or 1200 inches per minute, it is obvious that 40 R. P. M. 55 of the knife drum will produce 30 inch lengths. If, however, the knife drum is 30 inches in diameter, then at 40 R. P. M., the average velocity of the circumference of the knife drum is the same as that of the paper so that no variations 60 in the speed of shaft 44 will be required and it need only revolve (as hereinafter explained) in the same manner as the shaft 39 which will be adjusted by the Reeves drive to turn at 40 R. P. M.

65 Inasmuch as the cutoff lengths assumed in the previously detailed example however were to be 120 inches, it became necessary as previously explained to decrease the average speed of the knife drums to 10 R. P. M. or one fourth of the 70 speed of the paper. Therefore, in order to bring the knife speed to the speed of the paper at the time of cutoff it was necessary during this period to obtain a speed on the knife drum quadruple the speed of shaft 39. Thus, the knife drums 75 are arranged for their cutting operation when

the shafts 44 and 39 and the pin 42 are in the relative positions shown in Fig. 6.

When the Reeves drive is adjusted to obtain cutoffs of, let us say, 60 inch lengths, it will be obvious that with the speed of the paper remaining the same, the knife drums must revolve at an average rate of 20 R. P. M. in order to produce twenty cutting operations per minute. Thus the angular velocity of the knife drums previously described will be, at their circumference, just 10 half the speed of the paper. The screw 54 is so designed for this adjustment of the Reeves drive that through a movement of the link 62, a corresponding rotation of the lever 68 about the shaft 69 is obtained moving the pin 42 to the 15 position shown in Fig. 8 for the period of cutoff. In this position of the pin 42 and shafts 39 and 44, the necessary ratio between center-to-center position of shaft 39 and pin 42 on the one hand and shaft 44 and pin 42 on the other hand must 20 be two to one.

Applying the formulae previously set forth,

$$\theta = 600$$

$$r = \frac{2}{1}$$

$$r\theta = 2 \times 600$$

25

or a speed of 1200 inches per minute, the exact speed of the paper.

And, apart from the formulae, for 60 inch lengths, the shaft 39 must be rotated at half the speed at which it would rotate for 30 inch lengths, so that the speed of the knife drums must be double the average speed of shaft 39 at 35 the cutoff interval. This condition obtains due to the above ratio of two to one as described.

When, for example, it is desired to cut off 40 inch lengths, the adjustments obtained through the screw 54 and link 62 for rotating the lever 40 68, is such as to position the pin 42 as shown in Figure 10 in which the center-to-center positions from shaft 39 to pin 42 and shaft 44 to pin 42 is in the ratio of four to three. It will be obvious, that with the speed of the paper still remaining the same, the knife drums must nevertheless rotate at an average R. P. M. of 30, so that their average angular velocity at the circumference by reason of the 30 R. P. M imparted by shaft 39 is 900 inches per minute.

50 Thus, again applying the formulae previously set forth,

$$\theta = 900$$

$$r = \frac{4}{3}$$

$$r\theta = \frac{4 \times 900}{3}$$

55

or a speed of 1200 inches per minute, again the exact speed of the paper.

In this instance again, the shaft 39, in order to produce cuts longer than 30 inches must be driven so that average speed or angular velocity of the circumference of the knife drums is slower than the speed of the paper and accordingly a radial ratio of four to three as shown in Fig. 10 must be obtained at the instant of cutoff.

The limit or normal condition is obtained for 30 inch cutoffs. Here it is obvious that 40 R. P. M. of the knife drums will produce the proper sizes. But since the circumference of the knife drums is 30 inches, the angular velocity of the knife drums produced by shaft 39 is $\theta = 1200$. Accordingly, a ratio of one to one at all times between the speeds of shafts 39 and 44 are required, and

65

70

75

this is obtained as illustrated in Fig. 12 by placing the shafts 39 and 44 in coaxial relationship. In this condition, the radius from the center of shaft 44 to the center of pin 42 remains constant throughout the entire revolution of the shafts.

It will be obvious that the ratio selected between shafts 31 and 39, that of five to one, is not an essential ratio: and that it may be any other ratio which will make possible various adjustments of the Reeves drive to produce a desired speed on shaft 39; it being obvious however that for different ratios between shafts 31 and 39, different curvatures of the slot 65 may be necessary. However, for any specific dimension of the knife drums and any specific speed of the paper, the radial ratios between 39-42 and 44-42 must be specific and definite for each specific size to be cut.

It will further be obvious that, in the illustration given, in order to obtain cuts shorter than 30 inches in length, it will be necessary to increase the speed of shaft 39 and to correspondingly raise the said shaft 39 to a position even above shaft 44 so that it will be higher than in the position shown in Fig. 12.

The specific dimensional limitations hereinbefore described are, of course, illustrative and are not intended to constitute a limitation upon the operation of my knife-cutting machine.

Adjustments of the connections from screw 54 to the lever 68 can be obtained for properly positioning the shaft 39 with respect to the shaft 44 for every desired size of sheet to be cut by the knives 23 and 24. In order to effect this I have found that corresponding changes in the Reeves drive for producing different sizes of cutoff sheets do not require the same corresponding adjustments of the lever 68, the adjustments of the lever 68 being greater than the proportionate change of the Reeves drive for one size cutoff than for another.

In Fig. 14 I have shown a set of curves which illustrates this. As shown in the curves, for doubling the speed of the Reeves drive from 50 R. P. M. to 100 R. P. M. it is necessary to turn the handle 53 through approximately seventeen revolutions whereas for increasing the speed of the Reeves drive from 100 R. P. M. to 200 R. P. M. it is necessary to turn the handle or Reeves control screw through approximately 10 revolutions. From the above description however, it will be noted that for each doubling of the output of the speed of the Reeves drive a corresponding constant linear movement of the pin 42 is necessary. Thus for example, in changing the Reeves drive from 50 R. P. M. to 100 R. P. M. a distance L linear adjustment of the shaft 39 was necessary. In changing the Reeves drive from 100 R. P. M. to 200 R. P. M. an additional distance of $2L$ movement of the shaft 39 is necessary as indicated in Fig. 12. In order, therefore, to maintain the proper linear movement of the shaft 39 in spite of the decreased number of turns necessary for the Reeves control screw at the higher speeds I have provided the cammed slot 65 in which the roller 66 moves for increasing the ratio of linear movement of the shaft 39 for every turn of the Reeves control screw at the higher speeds.

In Fig. 1 I have illustrated a modified form of the principle enunciated in connection with Fig. 4, the main distinction being in the use of a link connection between the driving shaft 139 and the knife drum shaft 144. As in the case of Fig. 75 4 a Reeves drive 111 is employed comprising the

cones 112 and 113 mounted on their respective shafts 115 and 131 and having the drive belt 114. As in the previous illustration the roll 121 of feed-rolls 120 and 121 is driven from the sprocket 116, sprocket chain 117, sprocket wheel 118 and the shaft 119 for feeding the material 122 past the knives 123 and 124. Knives 123 and 124 are mounted on the drums 125 and 126, respectively.

The Reeves shaft 131 carries the sprocket 132 which drives the sprocket chain 133 and through the sprocket wheel 134 mounted on the shaft 135 and driving the pinion 136 through the idler gearing 137 thus driving the gear 138 which is secured to and rotates the shaft 139. A Reeves control screw handle 153 rotates the screw 152 on which is mounted for axial movement the bifurcated link 151 which engages and moves the belt 114. A second adjusting handle 129 rotates the screw 128 which axially moves the nut 155 and through a pin 156 attached to nut 155 entering into the slot of the bifurcated pin 157 drives the shaft 158 and through the lever 161 and link 162 which is connected by a universal joint 162' to one end of the lever 168, which has the rotation shaft 169 as to fulcrum, the opposite end of the lever 168 rotatively carries the shaft 139. Secured to and rotatable with the shaft 139 is the crank arm 171 which carries at its outer extremity a connecting link 172 for connecting the crank arm 171 and the crank arm 173 which is adjustably secured to the knife shaft 144 through an adjusting mechanism 174 shown in greater detail in Figs. 2 and 3 to be described hereinafter.

In this case as in Fig. 4 rotation of the Reeves control screw through handle 153 will produce changes in the R. P. M. of the drive shaft 139 which, through the cranks 171 and 173 and link 172 drives the knife shaft 144. At the same time rotation of the handle 129 drives the lever and link 161 and 162 to in turn rotate the lever 168 for adjusting the shaft 139 to move its center toward or away from the center of shaft 144, one limit being that position in which the shafts 139 and 144 are co-axial and the other limit being that position in which the shaft 139 is at its maximum distance away from shaft 144 as illustrated in Fig. 7, this maximum distance being determined of course by the cranks and levers 171, 172 and 173. It will be understood, of course, that the first limit mentioned, that of the co-axial position of shaft 139 and 144 may be even further extended so that even shorter pieces of the web will be cut simply by raising shaft 139 above shaft 144 and thus beyond the co-axial previously mentioned. As in the case of Fig. 4 when the shaft 139 is co-axial with shaft 144 a one to one ratio between the R. P. M. of shaft 139 and shaft 144 obtains throughout the revolutions, this being equal to and in synchronism with the paper, it being fed past the knives by the feed rolls 120 and 121. This is a condition obtained in Fig. 13 in which the shaft 139 and the shaft 144 are in co-axial relation and the crank 171 is shown extending to the pin 172' connecting this crank 171 to the link 172 and the link 172 is shown extending to the pin 175 connecting the link with the crank 173. At this position the knives 123 and 124 are in their cutting position and the cutting operations begin. For cutoffs 120 inches long and assuming all the conditions assumed in connection with Fig. 4, that is a movement of the paper of 100 feet or 1200 inches per minute a circumference of the knife drum of 30 inches the average R. P. M. of the shaft 139 will be one-fourth of the speed assumed in the first condition illustrated 75

in Fig. 13. Therefore during the cutoff period the ratio of four to one, in order that the shaft 144 may move at an angular speed which will produce a linear movement synchronous with the linear movement of the paper being cut. To this end at the instant of cutoff the center distance from shaft 139 to pin 172' and of shaft 144 to the center of pin 172' must be in the ratio of four to one at the period of cutoff or at the period when the knives are cutting. Similarly, as has been explained in detail in connection with Fig. 4 for cutting strips of material of 60 inch lengths the center-to-center ratios between the respective shafts 139 and 144 and the pin 172' must be two to one at the period of cutoff as illustrated in Fig. 9, and for cutting 40 inch lengths the ratio between the respective shafts 139 and 144 and pin 172' must be four to three at the period of cutoff as illustrated in Fig. 11.

It will be noted however, that due to the link and crank construction here employed the angular position of the cutting knives, which is determined by the angular positions in turn of the links 172 and 173 at the pin 175, is different for each particular size of material being cut so that it becomes necessary not only to adjust the shaft 139 to obtain the different ratios between the speed of the shaft 139 and the knife shaft 144 at cutoff but it also becomes necessary to angularly adjust the knives so that they will be in a cutting position at the new angular position assumed by the crank 173 and link 172 at the pin 175 for the new cutoff length. To explain this further, assuming that the knives are adjusted on the drum so that cutoff takes place when the pin 175 and the crank 173 is in the position shown in Fig. 13, it will be obvious that in the opposite extreme position shown in Fig. 7 the knives are not in cutting position at the time of the desired speed of shaft 144. It is however at this particular position of the pin 175 of Fig. 7 that the desired speed ratio between the driving drum 139 and the knife drum 144 obtains and therefore it is necessary to obtain a further adjustment of the knives so that they will be cutting when this proper ratio obtains. To this end I provide a further angular adjustment of the knives in relation to the crank 173 by means of the mechanism 174 shown in greater detail in Fig. 2.

Crank 173 as shown in Fig. 2 is keyed to a shaft 181 which has an extension 182 provided with a plurality of grooves 183 mounted on shaft 144. It is slidably connected, the coupling piece 185 having mounted at its extreme end a plurality of rollers 186 mounted on pins 187. Coupling 185 is also provided with a groove 188 in which it engages a fork 189 which is rotated by means of shafts 190.

When the shaft 158 is rotated in the manner described above the crank 191 rotates and moves and in turn moves the link 192 connected at its other end through the crank 193 to the shaft 190. Shaft 190 is thus rotated so it will be imparting an axial movement to coupling 185 through the fork 189 by appropriate curvature of the cam grooves 183. The pins 187 turn shaft 144 in relation to shaft 181 and in turn with relation to crank 173 thus providing an angular adjustment of the knives with respect to the crank 173 sufficient to compensate or correct for the angular adjustment necessary as indicated in comparing Figs. 7, 9, 11, and 13.

It will be understood by those skilled in the art that as crank 173 and link 172 are straightened this angular adjustment of the knife in rela-

tion to the position of pin 175 becomes smaller and smaller until at a proper angle between crank 173 and link 172 substantially no correction is necessary.

In view of the fact that the Reeves control screw is separate from the adjustment of the shaft 139 obtained through the adjusting handle 129 a definite relation between the rotation of handles 153 and 129 must be obtained. This is provided by the two indicator and scale combinations 194 and 195. These are so calibrated that for a predetermined rotation of handle 153 as indicated by the indicator 194 a corresponding rotation of handle 129 is necessary as in turn indicated by the indicator 195 for producing the proper adjustment of shaft 139 for any operation of the Reeves drive.

The different sheet lengths are marked on the dial by calibration. It is merely necessary to bring the two indicators to the corresponding positions on their dials.

In Figure 5 I have shown a further modified form of my invention in which the Reeves drive 311 comprises the cones 313 and 314, connected by the belt 312. The cone 313 mounted on and rotating the shaft 315 operates the feed rollers 320 and 321 for feeding the paper to the knives or cutters 323 and 324. The cone 318 secured to and driving the shaft 331 rotates the sprocket wheel 332 keyed to the shaft 331. A continuous sprocket chain 333 driven by the sprocket wheel 332 meshes at its opposite end with the teeth of sprocket wheel 334. Sprocket wheel 334 is keyed to and drives the shaft 335 at the opposite end of which is secured the worm gear 336 which meshes with the worm 337 mounted on the shaft 338. Secured to the side of and rotated by gear 336 is the pin 341 which extends from gear 336 to the wheel 342 which is driven by the gear 336 through the pin 341. (Pin 341 being shown partially broken away for clarity.) Wheel 342 is suitably supported in bearings on the shaft 344. Pin 341 also carries the crank levers 345 and 346 to which is secured the ends of the knife 323 in any suitable manner as by rivets 347. As gear 336 rotates it will carry the pin 341 in a path co-axial with the shaft 335 causing through the crank levers 345 and 346 the knife 347 to move from an arcuate to a curved path, as illustrated in greater detail in Figures 18, 19, 20, and 21, to be explained hereinafter. At the same time knife 324 describes the same sort of path driven through shaft 338, having secured at its lower end the worm 351 which meshes with a worm gear 352 to which is secured the pin 353 carrying at its other end the wheel 354 suitably mounted in bearings on shaft 355 and supporting the crank levers 356 and 357.

A Reeves drive adjusting handle 361 secured to the shaft 362 drives the bevel gear 363 meshing with the bevel gear 364 which in turn is secured to and rotates the shaft 365 and through this drives the bevel gear 366 meshing with bevel gear 367 for turning the screw 368. As screw 368 rotates, it moves the fork member 369 axially and adjusts the belt 312 for changing the R. P. M. of the output of the Reeves drive at shaft 331 to vary the cycle of the knives 323 and 324 for varying the size of cuts as explained hereinbefore. Secured to the shaft 362 are the worms 371 and 372 which mesh with the worm gears 373 and 374 respectively mounted on shafts 375 and 376. Secured to and driven by the shaft 375 is the crank arm 377 and the crank arm 378 which are connected through pins to their respective links 75

379, the opposite ends of which are connected through pins to the crank arms 345 and 346 respectively.

When the adjusting handle 361 is rotated it will, as will now be obvious move the belt 312 for adjusting the speed output of the Reeves drive and at the same time will adjust the position of the knives 323 and 324 so that the cutting action will occur at that point in the cycle at which the knives are moving in synchronism with the paper.

Referring now more specifically to Figures 18 to 21 which illustrate the paths taken by the knives in this form of the invention, it will be noted that the movement of the knives is a composite of both the circumferential movement affected by the pin 341 driven by gear 336 and a modification of that circumferential movement affected by the crank and link connections 377 and 379. With the particular adjustment of the links affected through rotation of the shaft 375 upon rotation of the hand wheel 361 the knives 323 and 324 are arranged to make the elliptical path illustrated in Figure 20 at curves 381 and 382. In taking this path the knives are arranged to be moving in synchronism with the paper at the time when they are in engagement with each other in the position shown in Figure 18. This is determined exactly in the manner already described in connection with the previous figures. Knowing for example, the ratio of the reduced speed to the normal speed at which the knives move in synchronism with the paper throughout their cycle, the link and crank connections are so designed and the adjustments so made as to increase the speed of the knife over the speed obtained at the gear 336 in the same ratio inversely as the gear is rotating less than the speed of the paper so as to bring the knives to synchronism with the paper, this increased speed being provided by the action of the crank and links 377 and 379.

Similarly for a further adjustment of the output speed of the Reeves drive, an entirely different path of the knives will be effected by a new adjustment obtained along the shaft 375, as illustrated in Figure 21 in the paths 383 and 384. Here again in order to obtain synchronism between the knives and the cutting paper during cutting operation, the crank and link connections are so adjusted that their action on the normal circumferential movement of the knife carrier will be such as to bring the knives into synchronism with the paper at the time when they meet for the cutting operation.

In Figure 17, I have illustrated this same principle in connection with knives mounted on crank members but which, however, eliminates the necessity for shaft 375 in Figure 5 and which requires only one set of links similar to 377 and 379 of Figure 5 for each knife instead of the two sets in Figure 5, and which will insure a uniform distribution of power during the entire cutting operation.

Here, as in the previous illustration, discs 401 and 402 are driven from the Reeves drive in a manner already described and which will now be clear to those skilled in the art, and through the pins 403 and 404 respectively secured to the cranks 405 and 406 will normally tend to rotate these members in a circumferential path.

Crank 405 is connected by connecting rods 407, 408 and 409 to crank 410. Crank 410 is in turn mounted on disk 411 by pin 412. It will thus be obvious that any rotation of disk 401 which

through pin 403 imparts a corresponding circular movement to crank 405 will also, through the connecting rods 407, 408 and 409, impart exactly the same movement to crank 410 causing it to move on its pin 412 which will be caused to rotate about the disc 411. Thus, disc 411 will be caused to rotate in exactly the same manner as disc 401 and the two cranks 405 and 410 will move synchronously. Although it is thus not essential, a drive belt 413 is mounted from disk 401 to disk 411 to further assure exactly synchronous movement, and to change disk 411 from a mere idler supporting disk to a power transmitting disk which will exert the same force upon crank 410 as disk 401 exerts upon crank 405.

The knife 414 is mounted upon connecting rod 409 and in a plane at right angles to that of connecting rod 409, the faces of the knives being in parallel planes. It will be obvious that every portion of the edge of the knife 414 will, at all times, be equidistant from the pins 403 and 412 through which power is transmitted to the knife 414 thus insuring a uniform power distribution over the edge of the knife 414.

In the same manner, crank 406, attached by pin 404 to disk 402, is connected by connecting rods 415, 416 and 417 to crank 418. Crank 418 is in turn mounted on disk 419 by pin 420. Disks 402 and 419 are also connected, in the manner previously described and for the same reasons, by a drive belt 421.

The knife 422 is mounted upon connecting rod 417 and in a plane at right angles to that of connecting rod 417 producing the uniform power distribution over the edges of the knife 422 in the manner previously described.

The action of disks 401 and 402 and their co-operating members is intended to be synchronous (since they are connected in the same manner to the Reeves drive), so that the knives 414 and 422 will cooperate with each other for the cutting operation, and will move in exactly homologous paths at all times.

A Reeves drive adjusting handle 461 secured to the shaft 462 drives the bevel gear 463 meshing with the bevel gear 464 which in turn is secured to and rotates the shaft 415 which in turn is connected in the manner described in connection with Figure 5 to adjust the R. P. M. output of the Reeves drive to vary the cycle of the knives 414 and 422.

Secured to the shaft 462 are the worms 471 and 472 which mesh respectively with the gears 473 and 474 respectively mounted on shafts 475 and 476. Secured to and driven by the shaft 475 is the crank arm 477 which is connected through a pin to the link 479. Similarly secured to and driven by the shaft 476 is the crank arm 478 which is connected through a pin to link 480. The opposite ends of links 479 and 480 are respectively connected by appropriate pins to their appropriate crank arms 405 and 406.

When the adjusting handle 461 is rotated it will, as has been explained, adjust the output speed of the Reeves drive and at the same time, in the same manner as explained in connection with Figure 5, will adjust the position of the knives 414 and 422 so that the cutting action will occur at that point in the cycle at which the knives are moving in synchronism with the paper.

In Figures 15 and 16, I have again illustrated the same principle in connection with a different adaptation of the crank and link members previously described. In these figures, the parts 561, 75

562, 564, 565, 571, 572, 573, 574, 575, 576, are exactly homologous to and act in the same manner as the parts in Figures 18 and 19 which are numbered 361, 362, 363, 364, 365, 371, 372, 373, 5
374, 375, and 376.

The disks 601 and 602 are driven through the Reeves drive in a manner which will now be understood. Attached to the sides of said disks are pins 603 and 604 respectively which in turn 10 carry cranks 605 and 606 respectively. Crank 605 carries knife 607 which in turn cooperates with knife 608 carried by crank 606.

Crank arm 609 is keyed to shaft 575 and carries at its other end pin 610 which is adapted 15 to slide in slot 611 in the crank 605. Similarly crank arm 612 is keyed to shaft 576 and carries at its other end pin 613 which is adapted to slide in slot 614 in the crank 616.

It will be obvious that the crank arm 609 20 will have an action similar to that of crank arm 477 of Figure 17, but that in place of the link 379 of Figures 18 and 19 there is substituted the length of the stroke of pin 610 in slot 611 of crank 605; the lower terminal of such stroke 25 corresponding to the pin which connects crank arm 377 and link 379 of Figures 18 and 19 and the other terminal of such stroke corresponding to the pin which connects link 379 with crank 305 of Figures 18 and 19.

30 Similarly, crank arm 612 has an action like that of crank arm 378 of Figures 18 and 19; but in place of link 380 of Figures 18 and 19, there is substituted the length of the stroke of pin 613 in slot 614 of crank 606.

35 When the adjusting handle 561 is rotated, it will, as has been explained, adjust the output speed of the Reeves drive and, at the same time, in the same manner as explained in connection with Figures 18 and 19 and Figure 5, will adjust 40 the position of the knives 607 and 608 so that cutting action will occur at that point in the cycle at which the knives are moving in synchronism with the paper.

Although I have described my invention in 45 detail, it will be apparent that I have chosen specific illustrations for the purpose of showing how to carry out my invention and I do not intend to be limited thereby except as set forth in the appended claims.

50 I claim:

1. In a power transmission system, a source 55 of power; a drum; a first shaft driven by said source of power; a second shaft connected to and driving said drum; a power transmission connection from said first shaft to said second shaft; means for adjusting the distance of the axis of the first shaft from the second shaft; said power transmission path from said source of power to said drum constituting a positive drive and being the sole transmission path to said drum.

2. In a power transmission system, a source 60 of power; a drum; a first shaft driven by said source of power; a second shaft connected to and driving said drum; a power transmission connection from said first shaft to said second shaft including a slideable pin and slotted member in which said pin slides; means for adjusting the axis of the first shaft with respect to the second shaft; said power transmission path from said source of power to said drum constituting a positive drive and being the sole transmission path to said drum.

3. In a power transmission system, a source 65 of power; a drum; a first shaft driven by said source of power; a second shaft connected to

and driving said drum; a power transmission connection from said first shaft to said second shaft including a slideable pin and slotted member in which said pin slides, said pin being carried by said first shaft and said slotted member being 5 mounted on said second shaft; means for adjusting the axis of the first shaft with respect to the second shaft; said power transmission path from said source of power to said drum constituting a positive drive and being the sole transmission 10 path to said drum.

4. In a power transmission system for driving a knife drum to cut a web in predetermined varying lengths, means for feeding said web at a 15 constant speed, a source of power; a knife drum carrying a knife; a first shaft driven by said source of power; a second shaft connected to and driving said drum; a power transmission connection from said first shaft to said second shaft; means for adjusting the axis of the first shaft 20 with respect to the second shaft; said power transmission path from said source of power to said drum constituting a positive drive and being the sole transmission path to said drum.

5. In a power transmission system for driving 25 a knife drum to cut a web in predetermined varying lengths, means for feeding said web at a constant speed, a source of power; a knife drum carrying a knife; a first shaft driven by said source of power; a second shaft connected to 30 and driving said drum; a power transmission connection from said first shaft to said second shaft including a slideable pin and slotted member in which said pin slides; means for adjusting 35 the axis of the first shaft with respect to the second shaft; said power transmission path from said source of power to said drum constituting a positive drive and being the sole transmission path to said drum.

6. In a power transmission system for driving 40 a knife drum to cut a web in predetermined varying lengths, means for feeding said web at a constant speed, a source of power; a knife drum carrying a knife; a first shaft driven by said source of power; a second shaft connected to 45 and driving said drum; a power transmission connection from said first shaft to said second shaft including a slideable pin and slotted member in which said pin slides; said pin being carried by said first shaft and said slotted member 50 being mounted on said second shaft; means for adjusting the axis of the first shaft with respect to the second shaft; said power transmission path from said source of power to said drum constituting a positive drive and being the sole transmission 55 path to said drum.

7. In a power transmission system for driving a knife drum to cut a web in predetermined varying lengths, means for feeding said web at a constant speed, a source of power; a knife drum 60 carrying a knife; a first shaft driven by said source of power; a second shaft connected to and driving said drum; a power transmission connection from said first shaft to said second shaft; said power transmission path from said 65 source of power to said drum constituting a positive drive and being the sole transmission path to said drum; and means for varying the speed of rotation of said first shaft, said means simultaneously shifting the axis of the first shaft with 70 respect to the second shaft to secure synchronism of speed between said knife drum and said web during the period said knife engages and cuts the web.

8. In a power transmission system for driving 75

- a knife drum to cut a web in predetermined varying lengths, means for feeding said web at a constant speed, a source of power; a knife drum carrying a knife; a first shaft driven by said source of power; a second shaft connected to and driving said drum; a power transmission connection from said first shaft to said second shaft including a slideable pin and slotted member in which said pin slides; said power transmission path from said source of power to said drum constituting a positive drive and being the sole transmission path to said drum; and means for varying the speed of rotation of said first shaft, said means simultaneously shifting the axis of the first shaft with respect to the second shaft to secure synchronism of speed between said knife drum and said web during the period said knife engages and cuts the web.
9. In a power transmission system for driving a knife drum to cut a web in predetermined vary-
- 10
- 15
- 20

ing lengths, means for feeding said web at a constant speed, a source of power; a knife drum carrying a knife; a first shaft driven by said source of power; a second shaft connected to and driving said drum; a power transmission connection from said first shaft to said second shaft including a slideable pin and slotted member in which said pin slides, said pin being carried by said first shaft and said slotted member being mounted on said second shaft; said power transmission path from said source of power to said drum constituting a positive drive and being the sole transmission path to said drum; and means for varying the speed of rotation of said first shaft, said means simultaneously shifting the axis of the first shaft with respect to the second shaft to secure synchronism of speed between said knife drum and said web during the period said knife engages and cuts the web.

GUSTAVE ADOLPHE UNGAR. 20
